US00D852177S

(12) **United States Design Patent** (10) **Patent No.:** **US D852,177 S**
(45) **Date of Patent:** **** Jun. 25, 2019**

(54) **MOBILE PHONE**

(71) Applicant: **Samsung Electronics Co., Ltd.**, Suwon-si (KR)
(72) Inventors: **Youngjun Cho**, Suwon-si (KR); **Sanghoon Song**, Gumi-si (KR); **Junyoung Lee**, Seoul (KR); **Munhee Jang**, Yongin-si (KR); **Youn-Gun Jung**, Suwon-si (KR); **Yoonyoung Choi**, Seoul (KR)
(73) Assignee: **SAMSUNG ELECTRONICS CO., LTD.**, Suwon-si (KR)

(**) Term: **15 Years**

(21) Appl. No.: **29/671,420**

(22) Filed: **Nov. 27, 2018**

Related U.S. Application Data

(63) Continuation of application No. 29/630,772, filed on Dec. 22, 2017.

(30) **Foreign Application Priority Data**

Jun. 23, 2017 (KR) 30-2017-0028975

(57) **CLAIM**

What is claimed is the ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the drawings depict portions of the mobile phone that form no part of the claimed design.

1 Claim, 7 Drawing Sheets

(58) **Field of Classification Search**

USPC 455/575.1, 556.2; D21/517, 329;
